UNITED STATES PATENT OFFICE.

JOSEPH E. GARLICK AND WALTER J. GARLICK, OF PATERSON, NEW JERSEY.

JACQUARD MECHANISM FOR LOOMS.

SPECIFICATION forming part of Letters Patent No. 443,235, dated December 23, 1890.

Application filed March 31, 1890. Serial No. 346,045. (No model.)

To all whom it may concern:

Be it known that we, JOSEPH E. GARLICK and WALTER J. GARLICK, citizens of the United States, residing at Paterson, in the county of 5 Passaic and State of New Jersey, have invented a new and useful Jacquard Mechanism for Looms, of which the following is a specification.

This invention relates to Jacquard mechanisms for looms; and it has for its object to construct a device or mechanism of this class whereby the efficiency of the loom shall be increased; by which a saving in power and in 10 wear upon the loom-harness, as well as in the material which is being woven, shall be effected, and which shall be simple in construction and readily applied.

The invention consists, mainly, in the construction and arrangement of two griffs, one 15 of which shall be vertically movable in the usual manner, and the other of which shall have a limited vertical movement, the latter being adapted to support or sustain in an elevated position such hooks as the pattern may 20 require to remain in an elevated position for more than one pick, thereby greatly lessening the strain upon the machinery, the wear upon the operating parts, and the power required to lift the hooks.

The invention further consists in the improved construction, arrangement, and combination of operative parts, which will be hereinafter fully described, and particularly 25 pointed out in the claims.

In the drawings hereto annexed, Figure 1 30 is a perspective view of our improved Jacquard mechanism. Fig. 2 is a vertical sectional view of the same. Fig. 3 is a vertical transverse sectional view taken on the line 40 $x x$ of Fig. 2. Fig. 4 is a vertical sectional view taken on the same plane as Fig. 2, but showing the upper griff in a raised position. Fig. 5 is a side elevation. Fig. 6 is a top plan.

Like numerals of reference indicate like 45 parts in all the figures.

To the frame of the machine, which is designated by 1, and which may be of any suitable construction, is journaled a rock-shaft 2, provided at one end with a lever 3, by means 50 of which it may be manipulated. The ends of the rock-shaft 2 are provided with arms 4 and 5, arranged on opposite sides of the frame,

each of said arms being provided with a cam-shaped slot 6, and the arm 4 is additionally provided with a sector-shaped rack 7, that engages a spur-wheel or pinion 8, secured upon a rock-shaft 9, journaled transversely in the frame.

11 11 designate cranks which are secured to the ends of the rock-shaft 9. The said 60 cranks are connected by means of links 12 with the hinged frame 13, in the upper end of which the pattern-cylinder or prism 14 is journaled in the usual manner. One end of said pattern-cylinder is provided with a star-wheel 65 15, having a number of points equal to the number of sides of the prism, usually four, and engaged by a hook or pawl 16, which is secured pivotally to the frame of the machine.

The sides of the frame 1 are provided with 70 bearings for the vertically-sliding rods 17, to the upper ends of which the griff-frame 18 is secured by means of set-screws or in any convenient manner. Said griff-frame is provided in the usual manner with the inclined knives 75 or blades 19, and it is provided with the upwardly-extending parallel flanges 20, having slots 21, that form guides for the lugs or studs 22, extending laterally from the grate-frame 23, which is provided with a number of transverse grate-bars 24 equal to the number of knives, in the rear of which they may be arranged. The lugs 22 at the front end of the frame are provided with friction-rollers 25, working in the rearwardly-inclined slots 26 80 85 in brackets 27, which are secured to the sides of the main frame of the machine. It will be seen that, owing to this construction, when the griff is raised the grate-frame will be moved in a rearward direction until the grate-bars will almost come into contact with the knives or blades of the griff.

The griff-frame 18 is provided on one side with a loop or staple 28, which encircles an arm 29, that extends upwardly from the pivoted hook or pawl 16. As the griff-frame is raised the hinged frame carrying the pattern-cylinder is thrown outward and the hook 16 engages the star-wheel of the pattern-cylinder, which is thereby partially rotated, so as 90 to present a new card to the needle mechanism. When the griff-frame has been raised, the staple 28 will engage the arm 29 and hold the hook or pawl 16 out of engagement with

the star-wheel, so that the second outward movement of the pattern-cylinder taking place during the lowering of the griff-frame shall have no effect upon the position of the pattern-cylinder.

5 The operation of raising and lowering the griff-frame is performed by means of the lever 3, attached to the rock-shaft 2, the arms 4 and 5 of which are provided, as described, 10 with cam-shaped slots 6. The said slots engage rollers 30 upon the ends of cranks 31, that are pivoted to the sides of the frame, and said cranks are in turn connected by pitmen 32 with the lower ends of the rods 17, to the 15 upper ends of which the griff-frame is secured. It will be seen that by manipulating the rock-shaft the slotted arms 5 and 6 will engage the rollers 30 upon the cranks 31 so as to swing the latter upon their pivots, thereby 20 raising or lowering the supporting-rods 17 according to the direction of the movement. By the same operation of the rock-shaft the segmental rack 7 will engage the pinion 8 upon the rock-shaft 9. The arms or cranks 11 of 25 the latter are connected, as above described, by the links 12 with the hinged frame 13, carrying the pattern-cylinder, and the parts are so proportioned that on the upward movement of the griff-frame 18 the said frame 13 30 shall be swung outward and back, which movement of frame 13 is repeated on the downward movement of the griff-frame. When the griff-frame moves upward and 35 while frame 13 swings outward, the star-wheel of the pattern-cylinder is engaged by the pawl 16, and said cylinder is partially rotated, so that a new pattern-card shall engage the needle mechanism when the griff-frame 18 is at the upper limit of its movement. At this time, however, the pawl 16 is 40 raised and held out of engagement with the star-wheel, so that when the frame 13 is vibrated on the downward movement of the griff-frame the position of the pattern-cylinder 45 shall not be changed. Hence it will be seen that each pattern-card is presented to the needle mechanism twice in succession, first when the griff-frame 18 is at the upper limit of its movement and again when it 50 secends.

Suitably mounted to slide vertically in the main frame 1 of the machine is the supplementary griff-frame 33, having transverse inclined knives 34. The griff-frame 33 is provided at its four corners with downwardly-extending lugs 35, to which are pivoted arms or links 36, the lower ends of which are in turn connected pivotally with links or levers 37, which are mounted pivotally upon the upper 55 right sides of the main frame 1. The knuckle-joints thus formed are connected by longitudinal connecting rods 38, so as to work in unison with each other. The links or levers 37 at the front of the machine are provided 60 with projections 39, having cam-shaped grooves 40. The rock-shaft 2 is provided with downwardly-extending arms 41, the lower

ends of which are provided with laterally-extending pins carrying friction-pulleys 42, adapted to engage the cam-grooves 40 for the purpose of manipulating the knuckle-joints supporting the griff-frame 33, as will be presently described.

44^a designate the longitudinally-sliding needles, which are mounted in suitable bearings in the frame 1, and which are so disposed as to be in alignment with the perforations of the pattern-cylinder. Springs 44 are arranged to force the needles automatically in a rearward direction and into such of the 75 perforations in the pattern-cylinder as are not covered by the pattern-card. The needles 44^a are provided in the usual manner with loops 45, through which extend the vertically-arranged hooks 46, which may be constructed of wire bent so as to form the hook-points 47 at their upper ends, and having their lower ends provided with upwardly-extending arms 48, which likewise terminate in the hooked points 49. Each of the so-called 80 hooks therefore virtually comprises a vertically-arranged body extending through the loop 45 in one of the needles and having two independent hooks 47 and 49. The lower ends of the hook-bodies 46 are connected with 85 guide-wires 50, extending through a perforated guide-plate 51, and the lower ends of 90 which are in turn connected in the usual manner with the harness of the warp-threads.

52 designates a grate-frame, which is suspended from the rock-shafts 2 and 9 in the frame 1 by means of links 53, and the bars of which simply serve to separate the vertically-movable hook-bodies 46. At the normal or initial position of the mechanism the griff-frame 18 rests in a lowered position upon the upper end of the frame 1, and the lower griff-frame 33 occupies a raised position. All of the hooks are at this time lowered, and the hooks 47 are in position to engage the upper 100 edges of the inclined knives 19, while the hooks 49 are some distance below the knives 34 in the griff-frame 33. At this time the springs 44 press the needles 44^a in a rearward direction, and such of said needles as are in alignment with the uncovered perforations in the pattern-cylinder enter said perforations, and the hooks controlled by said needles will consequently be in engagement with the griff-blades 19. When the rock-shaft 2 105 is oscillated by depressing the lever 3, the griff-frame 18 will be moved in an upward direction, and the hinged frame 13, carrying the pattern-cylinder, will be at the same time swayed in an outward direction, causing the pattern-cylinder, by the engagement of the star-wheel 15 with the hook or pawl 16, to be partially rotated and the next pattern-card to 110 be presented to the needle mechanism. As the griff-frame 18 moves upwardly, the grate-frame 23 will be moved in a rearward direction by the action of the guide-pulleys 25 115 engaging the rearwardly-inclined slots 26 in the brackets 27, and this rearward movement

of the grate-frame will continue until the grate-bars 24 press such of the hooks 47 as are in engagement with the knives 19 into close contact with the edges of said knives, 5 thereby preventing any of the hooks from being accidentally dropped. The upward movement of the griff-frame 18 of course ceases when the crank-arms 31 have assumed an approximately vertical position; but the length 10 of the cam-slots 6 is such as to permit the oscillation of the rock-shaft 2 to be continued until the rollers 42 upon the arms 41 of said rock-shaft engage the cam-grooves 40 upon the links or levers 37, which form a part of 15 the knuckle-joints supporting the lower griff-frame 33. The latter will thus be lowered to a position in which the hooks 49 may engage the knives 34. At this time the pattern-cylinder is in position to engage the needles 44^a, 20 and consequently the hooks 49, controlled by such of the needles 44^a as are in alignment with the open spaces in the pattern-card, will engage the knives 34 and remain supported upon the latter, when by a reverse movement 25 of the rock-shaft 2 the griff-frames are restored to their respective normal positions preparatory to a repetition of the operation, and the pattern-card is a second time presented to the needle mechanism. It is obvious that 30 such of the hooks as should be up for a number of picks will be maintained in an elevated position as long as the needles controlling said hooks register with the perforations in each succeeding pattern-card. When the 35 needles are pushed forward by a pattern-card, the hooks controlled thereby are thrown off the knives of the lower griff and caused to descend. On the downward movement of the upper griff-frame the grate-frame 23 is 40 moved forward and restored to normal position by the friction-rollers 25 engaging the slots 26. The hooks 49, controlled by such of the needles 44^a as are not in alignment with the open spaces in the pattern-card, will be 45 out of engagement with the knives and will be lowered with the griff.

It will thus be seen that by our improvement such of the hooks as are connected with warp-threads, which it shall be necessary in 50 the production of a certain pattern to raise repeatedly in the formation of the shed, are actually raised but once and remain supported in an elevated position until the particular warp-threads controlled by such hooks are to 55 be dropped, when the said hooks will be automatically restored to a lowered position by the needle mechanism, which is controlled in the usual manner by the pattern-card; and inasmuch as by this invention the individual 60 hooks are manipulated much less frequently than heretofore it will be readily seen how a considerable saving in power and in wear upon the parts of the mechanism is effected.

Having described our invention, what we 65 claim is—

1. In a Jacquard mechanism, the combination, with the vertically-movable griff-frame,

of the laterally-reciprocating grate-frame and mechanism for forcing the latter in a rearward direction simultaneously with the 70 upward movement of the griff-frame to place the bars of said grate-frame in contact with the upper ends of the hooks, which are thereby retained securely upon the knives of the griff, substantially as set forth.

2. The combination, with the vertically-movable griff-frame, the sides of which are provided with flanges having guide-slots, of the 75 grate-frame having guide-pins extending into the said slots and provided with friction-rollers, and brackets attached to the frame of the machine and having upwardly and rearwardly inclined guide-slots for the said friction-rollers, substantially as set forth.

3. In a Jacquard mechanism, the combination 80 of the frame, the vertically-movable guide-rods, the main griff-frame mounted upon the latter, cranks or arms connected pivotally with the sides of the frame, friction-rollers upon the said arms, pitmen connecting 85 said arms or cranks with the lower ends of the guide-rods carrying the griff-frame, a rock-shaft journaled in the main frame, and arms extending from the said rock-shaft and having cam-shaped slots engaging the friction-rollers at the outer ends of the pivoted 90 arms, substantially as set forth.

4. In a Jacquard mechanism, the combination 95 of the main griff-frame, vertically-movable guide-rods supporting the same, the lower griff-frame supported upon knuckle-joints 100 consisting of links or levers pivotally connected, the arms pivoted to the sides of the main frame, friction-rollers upon the said arms, the pitmen connecting said arms with the guide-rods of the main griff-frame, the rock-shaft having arms provided with cam-shaped slots engaging the friction-rollers at the outer ends of the pivoted arms, said cam-slots being of sufficient length to enable the 105 oscillation of the rock-shaft to be continued after the limit of the movement of the pivoted arms has been reached, and arms extending downwardly from the rock-shaft and having friction-rollers adapted to engage cam-grooves in projections formed upon the front 110 knuckle-joints, which latter are thereby operated while the upper griff-frame is at rest in a raised position, substantially as set forth.

5. In a Jacquard mechanism, the combination, with the hooks having auxiliary hooks 115 near their lower ends, of a lower or auxiliary griff-frame supported vertically movably upon knuckle-joints and adapted to engage and support such of the hooks as are raised 120 by the upper griff-frame until the warp-threads controlled by such hooks are to be dropped, and mechanism for operating the 125 knuckle-joints to lower and raise the auxiliary griff-frame, substantially as set forth.

6. In a Jacquard mechanism, the combination 130 of the main frame, the hinged frame carrying the pattern-cylinder, provided with a star-wheel, a pawl pivoted to the main frame

and having an upwardly-extending arm, the vertically-reciprocating griff-frame, the guide-rods supporting the same, the arms pivoted to the sides of the main frame, the friction-rollers upon said arms, the pitmen connecting said arms with the guide-rods of the griff-frame, a rock-shaft journaled in the main frame and having arms provided with cam-slots engaging the friction-rollers at the outer ends of the pivoted arms, a segmental rack on one of said arms engaging a pinion, a rock-shaft in the main frame carrying said pinion at one end thereof, links connecting cranks or arms extending from said rock-shaft with the hinged frame carrying the pattern-cylinder, and a staple secured to the griff-frame and encircling the arm extending upwardly from the pawl that operates the pattern-cylinder, substantially as and for the purpose set forth.

7. In a Jacquard mechanism, the combination, with the hooks provided near their lower ends with auxiliary hooks, of the upper or main griff-frame, the lower or auxiliary griff-frame, mechanism for vertically reciprocating the upper griff-frame, mechanism for vertically reciprocating the lower griff-frame while the main griff-frame is at rest in its raised position, the pattern-cylinder mechanism for partially rotating the latter during

the upward movement of the main griff-frame only, the needles, and mechanism for moving the pattern-cylinder toward and from the latter, substantially as and for the purpose set forth.

8. In a Jacquard mechanism, the combination of the main griff-frame, mechanism for vertically reciprocating the same, the auxiliary griff-frame, means for vertically reciprocating the latter while the main griff-frame is at the upper limit of its movement, the hooks having auxiliary hooks to engage the knives of the auxiliary griff-frame, the needles, the pattern-cylinder, means for partially rotating the latter on the upward movement of the main griff-frame only, and means for moving the pattern-cylinder to and fro to place the same pattern-card in engagement with the needles twice in succession, first when the main griff-frame is at the upper limit of its movement and again when it is restored to its initial position, as set forth.

In testimony that we claim the foregoing as our own we have hereto affixed our signatures in presence of two witnesses.
